CAPPING MACHINE

Hugh Mair, Cranford, N. J., assignor to The
Distillers Company Limited, Linden, N. J., a
corporation of Delaware

Application May 22, 1941, Serial No. 394,570

9 Claims. (Cl. 226—81)

This invention relates to improvements in capping machines, and particularly to machines for sealing liquid containers, the principal object of the invention being to provide a machine of this character in which the capping operation is automatically controlled by the container being sealed, the operation being performed without jarring the container or spilling its contents.

A further object of the invention is to provide a machine specially adapted for sealing containers having lever-type closures, the lever-actuating mechanism being automatically operated.

A further object of the invention is to simplify the general construction of a machine of the character set forth and at the same time to provide a machine which is time-saving and economical in operation and of maximum productive capacity.

Other objects and advantages of the invention will appear as the description proceeds.

In the drawings accompanying this specification,

Fig. 1 is a side elevation of a machine constructed in accordance with the present invention, parts being shown in section;

Fig. 2 is a front elevation of the machine shown in Fig. 1, portions being broken away;

Fig. 3 is a front elevation showing on a larger scale a portion of the mechanism shown in Fig. 2 and also showing a container approaching the capping position;

Figs. 4 and 5 are partly sectional detail side views illustrating the capping mechanism in different positions during its operation;

Fig. 6 is a partly sectional plan view of the machine taken on line 6—6 of Fig. 1;

Fig. 7 is a detail perspective view of a special lever assembly for initiating the operation of the capping mechanism; and

Fig. 8 is a similar perspective view showing the pressure block and the associated cam ears for controlling the tongue member for locking the bottle cap in sealing position upon the neck of the bottle.

Referring to the drawings, 1 designates generally the frame of the machine, above which is supported a hopper 2 communicating at its lower end with a chute 3 for supplying caps to be secured on the bottles or other containers as they arrive at the proper position. On the front wall of the machine frame is supported an L-shaped bracket forming a rest plate or container support 4 bevelled at opposite sides thereof to extend partially over a pair of rollers or pulleys 5 and 6 mounted for rotation on stud shafts 7 and 8 se-

cured in the front wall of the machine frame, said pulleys carrying travelling conveyors 9 and 10 respectively in alignment with each other across the container support 4. Also secured on the front wall of the machine frame, but spaced therefrom by interposed blocks 11, is a guide bar 12 of L-shape in cross section, said guide bar being disposed at such a distance above the rest plate 4 that the horizontal portion of the guide bar is spaced from the rest plate a distance slightly less than the height of the container to be capped.

Coincidentally pivoted at 13 on the horizontal portion of the guide bar 12 and in superimposed relation to each other are a pair of levers 14 and 15, the lowermost lever 14 having a cam portion 14^a the cam edge of which normally projects beyond the edge of the horizontal portion of the guide bar, as indicated in broken lines in Fig. 6, and intersects a vertical line passing approximately through the center of the container support 4 in position to be engaged by successive containers as they pass from the conveyor 9 to the container support, as hereinafter more fully described. The lever 15 is of less width than the lever 14 and carries an adjustable contact pin 18 for contact with a similar pin carried by a microswitch 19 secured to the vertical back portion of the guide bar 12. A bell-crank lever 16 pivotally mounted, as at 17, on a portion 16^b extending laterally from the lever 14 is provided with a downwardly extending flange 16^a the inner surface of which normally lies contiguous to the front edge of the lever 14, said flange serving to engage the edge of lever 15 during the inward movement of lever 15 thereby to ensure sufficient movement of lever 15 with lever 14 to bring about substantial contact of the pin 18 with microswitch 19. A spring 20 secured at one end to the bent up end of a bracket 12^a extending laterally from the guide bar 12 and at its opposite end to a pin carried by the lever 14 at the end thereof opposite from the cam portion 14^a, serves to return the levers 14 and 15 to normal position after operation in the manner hereinafter described.

Mounted for sliding movement vertically on the front wall of the machine frame is a pressure device, which comprises a capping head 21 disposed above the guide bar 12, said capping head being secured to the upper end of vertically extending pressure bar 22 which is slidable in the space formed by the spacing blocks 11 between the guide bar 12 and the machine frame, said pressure bar having associated with its lower end

a compression spring 23 for regulating the amount of pressure on the cap. Secured in the capping head and pressure bar respectively are a pair of narrow plates 24 and 25 which extend rearwardly through guide openings in the machine frame and support at their rear ends an electromagnet in the form of a solenoid 26. Pivotaly supported on an upright stud 27 secured in the upper plate 24 is a lever 28 formed of a pair of crossbars pivotally connected at their rear ends by means of a link 29 to the armature 30 of the solenoid 26. At its forward end the lever 28 carries a depending link 31, to the lower end of which is pivoted a depending tongue-like member 32. Formed on the forward end of the capping head, at opposite sides thereof, are a pair of ears 21^a, between which the member 32 is vertically slideable, said ears being provided with cam slots in which are guided pins 33 extending laterally from the member 32. Pivoted on one side of the capping head 21 is a three-armed lever 34, having a flange 34^a at the lower end of its vertical arm in position to engage the bell crank 16 when the lever 34 has been swung on its pivot, thereby to swing the bell crank on its pivot and move the flange 16^a out of the path of lever 15 after actuation of the microswitch 19. For actuating the lever 34, the pivot pin 35 connecting the member 32 with the link 31 is elongated so that it extends through the cam slot at that side of the capping head on which the lever 34 is located and one arm of said lever extends across said cam slot into the path of said pin 35 whereby as the pin moves downward in the cam slot it will engage the lever 34 and swing it on its pivot as shown in Fig. 5.

Pivotaly supported on a lug 36 near the lower end of the machine frame is a crossbar 37, the front end of which projects through the wall of the machine frame and is pivotally secured as at 38 to the pressure bar 22, as shown in Fig. 1. The crossbar 37 is further pivotally connected near its rear end as at 39 with the armature of a solenoid 40 suitably supported in the machine. A second micro switch 41 is mounted on the rear wall of the machine frame in position to be operated by a pin 42 carried by the crossbar 37 when said crossbar is swung upward on its pivot, a compression spring 43 being disposed between the armature and the crossbar 37 to cushion the impact of the pin 42 against the pin of microswitch 41.

A pair of magnetic switches conventionally illustrated at 44 and 45 herein are suitably mounted at any convenient part of the machine frame. These switches may be of any well known double-pole type. As shown in Fig. 1 both switches are provided with a pair of movable circuit-closing members *a* normally in open-circuit position and a solenoid *b* which when energized will attract said members to circuit closing position. The poles of switch 44 are connected by wires 46 and 47 in series with its solenoid *b* and with the micro-switch 19 supported on the guide bar 12, lead wires 54 and 55 from a suitable source of current being also connected with said poles. The circuit-closing members *a* in said switch 44 are connected to binding posts *c* which in turn are connected by wires 48, 49 with the electromagnet 40. The poles of switch 45 are connected by wires 50, 51 in series with its solenoid *b* and with the micro-switch 41, lead wires 56, 57 from a suitable source of current being also connected with said poles. The circuit-closing members *a* in switch 45 are also con-

nected to binding posts *c* which in turn are connected by wires 52, 53 with the solenoid 26.

The operation of the machine is as follows:

With the machine at rest, both of the microswitches 19 and 41 are open. Fig. 3 shows a bottle 58 which has been moved by the feed conveyor 9, so that approximately half of its width is over the container support 4. At this point the neck of the bottle is in the proper position to engage the foremost cap 59 at the lower end of the chute 3 so that as the bottle progresses further on to the support it will take the cap along with it. A butterfly damper pivoted as at 60 on the guide bar 12 near the end of the chute 3 serves to check the flow of caps at the delivery end of the chute.

The damper comprises a bushing 61 through which the pivot pin 60 passes, said bushing having a pair of radially extending arms 62, 63, and a segmental stop portion 64 formed integrally therewith. Normally the arm 63 extends across the lower end of the chute and the segmental portion 64 abuts against the free end of a flat spring 65 secured at its opposite end on the guide bar 12, as shown in broken lines in Fig. 6, thereby to retain the caps remaining in the chute after removal of the leading cap by a passing bottle. In practice, the arm 62 is acted upon by a spring in order to swing the damper back to normal position after the removal of each succeeding cap, said spring being omitted from the drawings for the sake of clarity, since the damper and its special arrangement of return spring are not claimed as a part of the invention. Now assuming that the conveyors 9 and 10 are traveling in the direction indicated by the arrows in Fig. 3 and that the conveyor 9 supports a continuous row of filled bottles placed side by side thereon, it will be readily seen that the foremost bottle will be pushed forward over the support 4 by the bottles following. As the bottle moves forward over the support its neck contacts with the cam portion 14^a of lever 14 and causes that lever to move inward on its pivot, carrying with it the lever 15 until its pin 18 comes into contact with the corresponding pin contact of microswitch 19, as shown in Fig. 6, thus preventing further movement of lever 15 with lever 14, so that the continued inward movement of lever 14 will cause lever 15 to move on its pivot in the opposite direction until the edge of its free end contacts with the flange 16^a whereby the lever 15 is again moved with lever 14 during the short further movement of the latter necessary to cause the pin 18 of lever 15 to impinge against the flexible contact pin of the micro-switch with sufficient firmness to operate the switch and close the circuit through magnetic switch 44 and electromagnet 40. The movement of levers 14 and 15 is such that the micro-switch 19 is closed when the bottle with the loose cap thereon is immediately below the capping head 21. Upon the closing of microswitch 19 current will flow through wires 55 and 47 to said microswitch and back through wire 46, solenoid *b* of magnetic switch 44, and wire 54 to the source. The said solenoid *b* being thus energized attracts the members *a* of magnetic switch 44 to circuit-closing position, whereupon current passes from lead wire 55 through one of the members *a*, wire 49, electromagnet 40 and back through wire 48, second circuit-closing member *a* of magnetic switch 44, and lead wire 54 to the source. The electromagnet 40 is thereby energized its plunger armature is raised and by means of its connection

39 with the crossbar 37 moves said crossbar on

its pivot thereby pulling down the pressure bar 22 and with it the capping head 21 until the latter engages the cap on the bottle and presses it into place on the bottle. As the plunger of the electromagnet 40 reaches its topmost position the pin 42 at the rear end of the crossbar 37 engages the corresponding pin of the microswitch 41 thus closing said microswitch and causing current to flow through wires 57 and 51 to the microswitch 41 and back through wire 58, solenoid *b* of magnetic switch 45 and wire 56 to the source. The said solenoid *b* being thus energized, attracts the members *a* of magnetic switch 45 into circuit-closing position, whereupon current will flow through wire 57, one of the contact members *a* of magnetic switch 45, wire 52, solenoid 26 and back through wire 53, second circuit-closing member *a* of magnetic switch 45 and lead wire 56 to the source. The solenoid 26 being thus energized, its plunger armature rises, thereby moving the lever 28 on its pivot and causing the depending member 32 to move downward into engagement with the upturned lever of the bottle cap and force said lever down to locked position as indicated in Fig. 5. During the downward movement of the depending member 32 the projecting end of its pivot pin 35 has engaged the lever 34 and swung it on its pivot so that by the time the depending member has reached its lowermost position the lever 34 has swung the bell crank 16 sufficiently to carry its flange 16^a out of the path of the lever 15, which remains immobile until the capped container is forced off the rest plate and on to the delivery conveyor by the containers following, whereupon the lever 14 is snapped back to normal position by its spring 20, carrying with it the lever 15 and thus breaking contact with microswitch 19 and de-energizing the electromagnet 40, so that the armature of said electromagnet drops, carrying with it the end of the crossbar 37 and permitting return of the capping head to normal position under the action of the weight of the plunger and lever 37. This movement of the crossbar 37 also carries its pin 42 out of contact with the microswitch 41 and consequently de-energizing the solenoid 26, thus permitting its plunger to drop thereby swinging the lever 28 on its pivot and returning the depending tongue member to its normal raised position.

In certain bottle capping machines heretofore in use with which I am familiar, the containers were fed to and discharged from the machine by a pair of conveyors traveling in laterally displaced parallel paths between which was mounted a reciprocable rest plate. In the operation of such machines the feeding conveyor delivers the containers, one after the other, on to the rest plate, which is then moved forward at right angles to the feed conveyor to carry the container under the cap chute, capping head and capping mechanism. After the cap has been sealed, special discharge mechanism pushes the capped container on to the discharge conveyor, the rest plate returning to its original position where it pauses while the next container is pushed on to it by the weight of the containers following. In certain other machines that have been proposed, although provided with feed and discharge conveyors disposed in longitudinal alinement with each other, the rest plate or work support is vertically reciprocable to carry the container to the capping mechanism, which is actuated by complicated mechanical devices that are set in operation after the arrival of a container at the 75

work support, all of which is time consuming. It will be obvious that in such constructions, only a fraction of the time required to complete one cycle is available for placing the container on the rest plate. This necessitates a rather high conveyor speed and a considerable number of containers on the feed conveyor in order to push the first container on to the rest plate in time. Moreover, a fixed stopper must be provided to limit the movement of the container to the proper position on the rest plate to have the cap compressed thereon, and the suddenness with which the container is brought up against this stopper invariably jars the container to such an extent as to cause spilling of the contents and wetting the outer surface of the container. This wetting causes trouble in the labeling machines, making it necessary to remove a considerable number of spoiled labels, thereby appreciably cutting down production. To overcome this loss it was necessary to have an operator take care of the spillage problem by holding a towel over the containers on the feed conveyor of the capping machine. This method, while effective in stopping spillage, is inefficient, and there is the possibility of lint from the towel getting into the container.

The machine herein described avoids the disadvantages above pointed out by providing a machine having a fixed container support in combination with feed and discharge conveyors disposed in alinement with each other across the container support and in which the entire capping operation is accomplished by the mere closing of a circuit through a solenoid, whereby the containers pass from the feed conveyor on to the container support, have their caps sealed in negligible time, as the movement of the solenoid plungers is instantaneous, after which the containers pass from the container support to the delivery conveyor, the entire course of travel of the container from the feed conveyor to the delivery conveyor being in a straight line whereby the capping operation is accomplished without any jarring or spillage whatever. By the use of this construction the conveyor speed required is not more than one-fourth that of the old machines, and due to the elimination of jarring and consequent spilling it is unnecessary to have a towel operator at the machine and consequently the possibility of foreign material getting into the containers is avoided. Moreover, as the capping operation is entirely automatic, no extra motor or clutch is required as in the old machine, and the construction is therefore considerably simplified.

Having thus described my invention, what I claim is:

1. In a capping apparatus, a container support, a capping head above the container support, an electromagnet including an armature connected to the capping head to move the latter in capping direction, means to move the capping head in the opposite direction, a container actuated trip to energize said electromagnet, and means actuated by movement of the capping head in a capping direction to de-energize the electromagnet.

2. In a capping apparatus, a container support, a capping head reciprocable above the container support, an electromagnet including an armature connected to the capping head to move the latter in capping direction, a micro-switch operable to close a circuit through said electromagnet, a container-actuated trip to actuate said micro-switch to circuit-closing position, means actuated by movement of the capping head in

capping direction to open said circuit thereby to de-energize the electromagnet, and means for returning the capping head to its initial position.

3. In a capping apparatus, a container support, a capping head reciprocable above the container support, an electromagnet including an armature connected to the capping head to move the latter in capping direction, a magnetic switch electrically connected with said electromagnet, means operable to close a circuit through said magnetic switch thereby to energize the electromagnet, a container-actuated trip to operate said circuit-closing means, means actuated by movement of the capping head in capping direction to open said circuit thereby to de-energize the electromagnet, and means for moving the capping head in the opposite direction.

4. In a capping apparatus, a container support, a capping head reciprocable above the container support, an electromagnet including an armature connected to the capping head to move the latter in capping direction, a magnetic switch electrically connected with said electromagnet, a micro-switch in electrical connection with said magnetic switch, a container-actuated trip to operate said micro-switch thereby to close a circuit through the magnetic switch and energize the electromagnet, means actuated by movement of the capping head in capping direction to open said circuit and de-energize the electromagnet, and means for returning the capping head to its initial position.

5. In a capping machine, a container support, a vertically reciprocable capping head above said support, a pivotally mounted bar pivotally connected to said head and normally retaining the same in its uppermost position, an electromagnet including an armature pivotally connected to said bar for moving the same on its pivot thereby to move the capping head in capping direction, means for energizing said electromagnet, a container-actuated trip to actuate said means, and means actuated by movement of the capping head in capping direction to de-energize the electromagnet and permit return of the capping head to its initial position under the action of said bar.

6. In a capping machine, a container support, a vertically reciprocable capping head above said support, a pivotally mounted bar pivotally connected to said head and normally retaining the same in its uppermost position, an electromagnet including an armature pivotally connected to said bar for moving the same on its pivot thereby to move the capping head in capping direction, a micro-switch operable to close a circuit through said electromagnet thereby to energize the same, container-actuated means to actuate said micro-switch, and means actuated by

movement of the capping head in capping direction to deenergize the electromagnet and permit return of the capping head to its initial position by the action of said pivoted bar.

7. In a capping machine, a container support, a vertically reciprocable capping head above said support, a pivotally mounted bar pivotally connected to said head and normally retaining the same in its uppermost position, an electromagnet including an armature pivotally connected to said bar for moving the same on its pivot thereby to move the capping head in capping direction, a magnetic switch electrically connected with said electromagnet, a micro-switch electrically connected with said magnetic switch and operable to close a circuit through said magnetic switch and electromagnet, a pivoted lever having means for actuating said micro-switch, container-actuated means to operate said lever into operative engagement with the micro-switch, and means actuated by movement of the capping head in capping direction to de-energize the electromagnet and permit return of the capping head to its initial position by the action of said pivoted bar.

8. In a capping machine, a container support, a vertically reciprocable capping head above said support, a pivotally mounted bar pivotally connected to said head and normally retaining the same in its uppermost position, an electromagnet including an armature pivotally connected to said bar for moving the same on its pivot thereby to move the capping head in capping direction, a magnetic switch electrically connected with said electromagnet, a micro-switch electrically connected with said magnetic switch and operable to close a circuit through said magnetic switch and electromagnet, a pivoted lever having means for actuating said micro-switch, a second pivoted lever having means for actuating said first lever into operative engagement with the micro-switch, container actuated means to actuate said second lever, and means actuated by movement of the capping head in capping direction to de-energize the electromagnet and permit return of all of the members to their initial positions under the action of said bar.

9. In a capping machine as set forth in claim 1, means carried by the capping head to engage and swing the lever of a lever-type cap into clamping position, a pivoted lever pivotally connected at one end thereof to said means, a second electromagnet having an armature pivotally connected to the opposite end of said lever, and means operative during movement of the capping head in capping direction to energize said second electromagnet prior to de-energization of the first electromagnet.
